C. FUCHS.
BED BOTTOM HANGER.
FILED JUNE 27, 1922.

INVENTOR.
Charles Fuchs
BY *William Jackson*
ATTORNEY.

UNITED STATES PATENT OFFICE.

CHARLES FUCHS, OF PHILADELPHIA, PENNSYLVANIA.

BED-BOTTOM HANGER.

Application filed June 27, 1922. Serial No. 571,190.

To all whom it may concern:

Be it known that I, CHARLES FUCHS, a citizen of the United States, residing at the city of Philadelphia, county of Philadelphia, and State of Pennsylvania, have invented certain new and useful Improvements in Bed-Bottom Hangers, of which the following is a specification.

This invention relates to improvements 10 in bed-bottom hangers and has special reference to a type of hanger designed to support the frame of a bed spring upon the usual or conventional side rail which connects the head and foot ends of the main 15 bedstead frame. The hanger of the invention is of particular service in connection with that type of bed bottom in which tubular side frames are employed.

The leading object of the present invention is to provide an improved bed-bottom hanger of simple and economical design which in manufacture costs no more than less efficient hangers now in general use. A further object resides in the provision of 25 general details of construction and arrangement and combination of parts for attaining the results sought by said leading object. A still further object is to make use of conventional angle-iron and by simple steps 30 of stamping and bending provide hanger parts possessed of maximum strength and rigidity. Other and further objects not at this time more especially referred to will appear hereinafter.

35 The invention consists of the improvements hereinafter described and finally claimed.

The nature, characteristic features and scope of the invention will be more fully 40 understood from the following description taken in connection with the accompanying drawings forming part hereof, and in which:

Fig. 1, is a fragmentary view, in cross-section, illustrating the manner of supporting the tubular side frame of a bed spring upon the side rail of a bedstead by means 45 of a hanger embodying features of the present invention.

50 Fig. 2, is a perspective view of the hanger parts detached.

Fig. 3, is a fragmentary view, in cross-section, illustrating the manner of supporting the tubular side frame of a bed spring 55 upon the side rail of a bedstead by means of a modified form of hanger, and

Fig. 4, is a perspective view of the latter hanger detached.

For the purpose of illustrating my invention I have shown in the accompanying drawings two forms thereof which are at present preferred by me, since the same have been found in practice to give satisfactory and reliable results, although it is to be understood that the various instrumentalities of which my invention consists can be variously arranged and organized and that my invention is not limited to the precise arrangement and organization of the instrumentalities as herein shown and described.

In the manufacture of my improved hanger I make use of angle-iron which I have found to be especially adapted for the purpose. The angle-iron is first cut into proper lengths. It has then stamped from 75 that part forming the vertical wall an angular recessed portion, a lug and a part formed upon an arc of a circle which extends from the base of the lug to the underside of the horizontal top wall. There is thus left projecting beyond the lug a horizontal wall devoid of a vertical wall. The projected portion is now bent upon an arc of a circle for engaging at least partially around the side frame of a bed spring. I 80 may make the hanger in two parts as shown in Figs. 1 and 2, or in one piece as shown in Figs. 3 and 4.

Referring now more especially to Figs. 1 and 2, 10 designates the vertical wall of the hanger and 11 the horizontal wall. The vertical wall at one end is recessed as at 12 to form a foot for resting upon the side-rail 13 of a bedstead. The opposite end of the vertical wall is cut away upon an arc of a circle 90 as at 14 so that the inner end of the horizontal wall is devoid of a vertical wall. There thus remains intermediate of the hanger ends a lug 15. This lug functions to prevent lateral movement of the hanger in one direction when it abuts against the side-rail 13. That part of the horizontal wall of the hanger which is free of a side wall is bent 95 upon an arc of a circle as at 16 for engaging partially around the side-frame 17 of a bed-spring. It is to be noted that the free end of part 16 extends in a plane well below the horizontal axis of frame 17 and that the horizontal wall of the hanger is in a plane well above the horizontal axis of frame 17. 105 The edge of the lug which is formed upon an arc of a circle engages the side frame sur-

face in opposed relation to the bent part 16 of the hanger. In addition the under surface of the side frame is engaged by the curved end 18 of a plate the opposite end of 5 which is flat, abuts against the underside of the hanger top and is secured thereto by means of a rivet 19. Penetrating the hanger top, the side frame and the curved end 18 of said plate is a vertically disposed rivet 20. 10 Since the frame is thus rigidly secured between the various parts above described axial movement of the frame is eliminated. Further by this special arrangement of parts should the rivet become loosened the hanger 15 itself is not apt to be shifted side-wise. In other words the maximum amount of frictional engaging surface serves to maintain the hanger and frame in proper position with respect to one another. I choose to 20 term this frictional engaging of parts a four-point suspension, namely at the top, bottom and opposed sides of the bed-spring side frame.

In Figs. 3 and 4, the construction is the 25 same as above described except that the parts are made integral instead of two pieces. In making the hanger that part of the horizontal, top piece which is free of a side wall is longer than that shown in the foregoing 30 construction and is first bent to provide a ring-like part 21 for engaging around the side-frame 17 and the free end of such part 21 is then bent over and extended in a horizontal manner as at 22 for abutting against 35 the underside of the top wall of the hanger. The horizontal portion 22 is riveted to the hanger top after the hanger has been fitted to the side frame. The four-point suspension is common to this style of hanger.

40 It will now be apparent that I have devised a novel and useful construction which embodies the features of advantage enumerated as desirable in the statement of the invention and the above description and while 45 I have in the present instance shown and de-

scribed the preferred embodiments thereof which have been found in practice to give satisfactory and reliable results, it is to be understood that the same are susceptible of modification in various particulars without departing from the spirit or scope of the invention or sacrificing any of its advantages. 50

What I claim is:

1. In a hanger of the character stated the combination of a side-tube, a member comprising a horizontal, flat top and a vertical side-wall said flat top terminating at one end in a downwardly curved portion for at least partially encircling said side-tube and said vertical wall forming a foot for seating the side-rail of a bed, a lug depending from said vertical wall in the same vertical plane for abutting against such side-rail to prevent lateral movement of the hanger and means for rigidly clamping the flat top of said member to the side-tube and to that portion of the hanger engaging around said side-tube. 55 60 65

2. In a hanger of the character stated the combination of a side-tube, a member comprising a horizontal, flat top and a vertical side-wall said flat top terminating at one end in a downwardly curved portion which partially encircles said side-tube and said vertical wall forming a foot for seating upon the side-rail of a bed said vertical wall having a depending lug for abutting against such side-rail to prevent lateral movement of the hanger, a second member having a flat portion in abutting fixed relation with the underside of the flat top of the first mentioned member and having a depending portion which is curved to fit around the lower part of the side tube and means passing through said tube and both of said members to form an interlock. 70 75 80 85

In testimony whereof, I have hereunto signed my name.

CHARLES FUCHS.
